UNITED STATES PATENT OFFICE

117,274

DESIGN FOR A TABLE TOP

John L. Ingram, Hebron, Ohio

Application March 28, 1938, Serial No. 76,139

Term of patent 14 years

To all whom it may concern:

Be it known that I, John L. Ingram, a citizen of the United States, residing at Hebron, in the county of Licking and State of Ohio, have invented a new, original, and ornamental Design for a Table Top, of which the following is a specification, reference being had to the accompanying drawing, forming part thereof.

I claim:

The ornamental design for a table top, as shown.

JOHN L. INGRAM.
